[57] CLAIM

The ornamental design for a vertical wave display panel, as
shown and described.

DESCRIPTION

FIG. 1 is a perspective view of a vertical wave display panel
showing our new design;

FIG. 2 is a top plan view thereof, the bottom plan view being
substantially the same;

FIG. 3 is a front elevational view thereof;

FIG. 4 is a rear elevational view thereof;

FIG. 5 is a side elevational view thereof, the other side being
a mirror image; and,

FIG. 6 is a fragmentary perspective view of a second
embodiment of a vertical wave display panel showing our
new design, the vertical wave display panel is broken in the
center to disclose indeterminate length.
